UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

CASING-CAP FOR LAMP-SOCKETS.

1,141,120.

Specification of Letters Patent.

Patented June 1, 1915.

Application filed November 15, 1911. Serial No. 660,345.

To all whom it may concern:

Be it known that I, CHARLES J. KLEIN, a citizen of the United States, residing at Milwaukee, in the county of Milwaukee and State of Wisconsin, have invented new and useful Improvements in Casing-Caps for Lamp-Sockets, of which the following is a full, clear, concise, and exact description, reference being had to the accompanying drawing, forming a part of this specification.

This invention relates to casings for lamp sockets and pendent switches, and with respect to its more specific features, to improve caps of such casings.

One of the objects of the invention is to provide an improved casing cap of sturdy construction which can be cheaply manufactured in any desired style.

20 Further objects will appear hereinafter.

The accompanying drawing is illustrative of my invention and shows two preferred embodiments thereof.

Figure 1 is a central sectional view of a 25 lamp socket casing; and, Fig. 2 is a similar view of a modified form of cap.

The casing illustrated is of the type described and claimed in my co-pending application filed June 6, 1910, Serial No. 30 565,203 and comprises a cylindrical shell 1 having a polygonal margin 2 adapted to fit within a polygonal rim 3 of a cap 4. The interfitting rims of these two members effectively lock the same against relative rotation. In order to lock the cap and shell against axial separation the shell is provided with one or more displaced catches 5 having cut edges arranged to snap over the lower face of an internal annular groove 6 35 formed in the cap rim 3. If desired, however, other forms of interlocking means may be provided on the overlapping portions of the casing sections.

It is desirable in casings of the type described that the threaded bushing be 45 strongly attached to the cap and that the body portion of the latter be of material sufficiently heavy to withstand the strain of supporting all the parts carried thereby. 50 On the other hand, it is desirable that the margin of the cap be of material sufficiently light and malleable to permit the formation

thereon of well-defined locking shoulders for engaging the shell. To accomplish these ends, and to facilitate manufacture of the 55 cap, the body portion 4 and rim 3 of the cap are made separately and of relatively heavy and light material respectively.

The bushing 8 of the cap is preferably 60 formed integrally with the heavy body portion 4, as shown in Fig. 1. If desired, however, the bushing may be separate and attached to the cap by riveting or other suitable manner, as shown in Fig. 2. The margin of the heavy body portion 4 of the 65 cap is provided with a transverse flange 7 to which the rim 3 is rigidly secured by spinning the same over both sides of the flange, as shown.

By forming the rim 3 separate from the 70 cap and of lighter material, the same may be readily manufactured and provided with interlocking shoulders of more efficient construction. For example, in the form shown in the drawing, the rim has a polygonal 75 margin and ledge thereabove. As will be apparent, the angular edges of the polygonal face at the ledge must be sharp and well-defined in order to produce an effective interlock with the shoulders of the shell. 80 Since the rim 3 is of relatively light material as described, the sharpness of the angular edges may be readily obtained in manufacture to a degree which would be impossible with a cap of relatively heavy material throughout. Furthermore, the rim 3 85 may be more readily and cheaply manufactured in the desired shape when formed separately from the cap, as it remains in the form of a ring open at both ends until 90 attached to the body of the cap.

What I claim as new and desire to secure by Letters Patent is:—

1. A cap for lamp socket casings comprising a dome portion of heavy stock having a spreading flange at its open end and a rim of relatively light stock beaded over said flange and rigidly secured to said dome portion, said rim having integral shoulders for engagement with a complementary 95 part.

2. A cap for lamp socket or similar casings, comprising a dome portion of heavy stock having an integral bushing at its con-

tracted end and a spreading flange at its open end, and a rim of relatively light stock beaded over said flange and rigidly secured to said dome portion, said rim having integral shoulders for engagement with a complementary part.

In witness whereof, I have hereunto sub-

scribed my name in the presence of two witnesses.

CHARLES J. KLEIN.
